(57) **CLAIM**

The ornamental design for a clip for waste bag, as shown and described.

DESCRIPTION

Clip for waste bag

6.1 : Perspective

6.2 : Left

6.3 : Right

6.4 : Top

6.5 : Bottom

6.6 : Perspective in Condition of Use

The equal-length broken lines in the drawings depict portions of the clip for waste bag that form no part of the claimed design. The dash-dot-dash lines indicate boundaries of the claim.
